(57) CLAIM

What is claimed is the ornamental design for a handbag, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a handbag.

FIG. 2 is a front view of the handbag.

FIG. 3 is a rear view of the handbag.

FIG. 4 is a right side view of the handbag.

FIG. 5 is a left side view of the handbag.

FIG. 6 is a bottom view of the handbag; and,

FIG. 7 is a top view of the handbag.

A handbag design is depicted. Particular emphasis is placed on the color scheme used to contrast against the dark brown of the handbag.
